CLAIM

The ornamental design for a mobile CCTV, as shown and described.

DESCRIPTION

FIG. 1 is a perspective view of a mobile CCTV showing my new design;

FIG. 2 is a front elevational view thereof;

FIG. 3 is a rear elevational view thereof;

FIG. 4 is a side elevational view thereof;

FIG. 5 is another side elevational view thereof;

FIG. 6 is a top plan view thereof; and,

FIG. 7 is a bottom plan view thereof.

The broken lines shown in the drawings depict portions of the mobile CCTV that form no part of the claimed design.
